(57) **ABSTRACT**
A new *Pelargonium* plant particularly distinguished by having
semi-double flowers with a white color, compact growth
habit and strong branching, is disclosed.

1 Drawing Sheet

1

Genus and species: *Pelargonium* sp.
Variety denomination: 'KLEIZ13338'.

BACKGROUND OF THE NEW PLANT

The present invention comprises a new and distinct variety of *Pelargonium*, botanically known as *Pelargonium* sp. and hereinafter referred to by the variety name 'KLEIZ13338'. 'KLEIZ13338' originated from a controlled cross between the female *Pelargonium* variety 'Cassandra' (U.S. Plant Pat. No. 6,220), having white flowers with medium branching and a strong growth habit, and the proprietary male *Pelargonium* variety 'PP 06 086' (unpatented), having orange flowers, with small branching and a small growth habit.

In June 2008 the two *Pelargonium* parental lines 'Cassandra' and 'PP 06 086' were crossed in Stuttgart, Germany and seeds were obtained. The seeds were sown and plants were grown for evaluation. A plant line was selected in June 2009 and named 'KLEIZ13338'. In June 2009 'KLEIZ13338' was first vegetatively propagated by vegetative cuttings. 'KLEIZ13338' was found to reproduce true to type in successive generations of asexual propagation via vegetative cuttings in Stuttgart, Germany.

**CROSS REFERENCE TO RELATED
APPLICATIONS**

Plant Breeder's Rights for 'KLEIZ13338' were applied for in Canada on Feb. 8, 2013, Application No. 13-7923. 'KLEIZ13338' has not been made publicly available or sold more than one year prior to the filing date of this application.

SUMMARY

The following are the most outstanding and distinguishing characteristics of this new variety when grown under normal horticultural practices in Stuttgart, Germany.

2

1. White flower color;
2. Semi-double flowers;
3. Compact growth habit; and
4. Strong branching.

DESCRIPTION OF THE PHOTOGRAPH

This new *Pelargonium* plant is illustrated by the accompanying photograph which shows an overall view of the plant. 10 The photograph is of a 4 to 5 month-old plant grown in Stuttgart, Germany under greenhouse conditions in May 2012.

The colors shown are as true as can be reasonably obtained by conventional photographic procedures.

DESCRIPTION OF THE NEW VARIETY

The following detailed descriptions set forth the distinctive characteristics of 'KLEIZ13338'. The data which define 20 these characteristics were collected from asexual reproductions carried out in Stuttgart, Germany. Data was collected on fifteen-week-old plants grown in an indoor trial in Stuttgart, Germany under greenhouse conditions in April 2013. Color references are to The R.H.S. Colour Chart of The Royal Horticultural Society of London (R.H.S.), 5th edition (2007). 25 Classification:

Family.—Geraniaceae.
Botanical.—*Pelargonium* sp.
Common.—*Pelargonium*.
Designation.—'KLEIZ13338'.

30 Parentage:
Female parent.—*Pelargonium* line 'Cassandra' (U.S. Plant Pat. No. 6,220).
Male parent.—*Pelargonium* line 'PP 06 086' (unpatented).

35 Plant:
Habit.—Upright.
Height.—20.0 cm.
Spread.—20.0 cm.

<i>Life cycle.</i> —Annual, January to April in a greenhouse, May to October outside.	5	<i>Apex.</i> —Acute. <i>Base.</i> —Obtuse. <i>Margin.</i> —Entire. <i>Texture (both surfaces).</i> —Smooth.																							
<i>Form.</i> —Rounded, potted plant.	10	<i>Color.</i> —Upper surface: RHS 138B. Lower surface: RHS 138D. <i>Length.</i> —0.9 cm. <i>Width.</i> —0.4 cm.																							
<i>Time to produce a rooted cutting.</i> —18 days.	15	<i>Pedicel:</i> <i>Length.</i> —0.5 cm to 1.2 cm. <i>Diameter.</i> —0.15 cm. <i>Color.</i> —RHS 138D. <i>Texture.</i> —Light short pubescence (a little rough). <i>Strength.</i> —Medium.																							
<i>Time to bloom from propagation.</i> —75 days.	20	<i>Peduncle:</i> <i>Length.</i> —10.0 cm to 15.0 cm. <i>Diameter.</i> —0.5 cm. <i>Color.</i> —RHS 137D. <i>Texture.</i> —Rough. <i>Strength.</i> —Medium.																							
<i>Lastingness of inflorescence on the plant.</i> —About 2 weeks.	25	<i>Reproductive organs:</i> <i>Stamens.</i> —Number: Mostly 5. Anther length: 0.2 cm Anther color: RHS N155C. Filament length: 0.6 cm. Filament color: RHS N155B. Pollen amount: Moderate. Pollen color: RHS 25D. <i>Pistils.</i> —Number: 1. Stigma color: RHS 68C. Style length: 0.1 cm. Style color: RHS 56D. Ovary arrangement: Erect. Ovary color: RHS 142D. Ovary length: 0.4 cm. Ovary diameter: 0.1 cm.																							
<i>Root type.</i> —Medium, freely branching.	30	Fruit and seed set: None observed. Disease and pest/insect resistance: None observed.																							
<i>Color.</i> —White.	35	COMPARISON WITH PARENTAL LINES AND KNOWN VARIETY 'KLEIZ13338' is a distinct variety of <i>Pelargonium</i> having violet ray florets and dark green leaves; 'KLEIZ13338' is distinguished from its parents as described in Table 1:																							
<i>Stems:</i>	40	TABLE 1 <table border="1"> <thead> <tr> <th colspan="4">Comparison with Parental Lines</th></tr> <tr> <th>Trait</th><th>'KLEIZ13338'</th><th>Female parent 'Cassandra'</th><th>Male Parent 'PP 06 086'</th></tr> </thead> <tbody> <tr> <td>Growth habit</td><td>Compact</td><td>Strong</td><td>Small</td></tr> <tr> <td>Flower color</td><td>White</td><td>White</td><td>Orange</td></tr> <tr> <td>Branching</td><td>Strong</td><td>Medium</td><td>Small, little</td></tr> </tbody> </table> <td><i>Fragrance.</i>—Absent.</td> <td>45</td> <td>'KLEIZ13338' is most similar to the commercial <i>Pelargonium</i> plant named 'Cassandra' (U.S. Plant Pat. No. 6,220). Differences between the two varieties are described in Table 2:</td>	Comparison with Parental Lines				Trait	'KLEIZ13338'	Female parent 'Cassandra'	Male Parent 'PP 06 086'	Growth habit	Compact	Strong	Small	Flower color	White	White	Orange	Branching	Strong	Medium	Small, little	<i>Fragrance.</i> —Absent.	45	'KLEIZ13338' is most similar to the commercial <i>Pelargonium</i> plant named 'Cassandra' (U.S. Plant Pat. No. 6,220). Differences between the two varieties are described in Table 2:
